UNITED STATES PATENT OFFICE.

ROSSETER I. TOWLE, OF GUNNISON, COLORADO.

SAFETY-WHEEL FOR ROLLER-SKATES.

SPECIFICATION forming part of Letters Patent No. 336,603, dated February 23, 1886.

Application filed May 13, 1885. Serial No. 165,322. (Model.)

To all whom it may concern:

Be it known that I, ROSSETER I. TOWLE, of Gunnison, in the county of Gunnison and State of Colorado, have invented a new and 5 Improved Safety-Wheel for Roller-Skates, of which the following is a full, clear, and exact description.

The object of my invention is to provide a new and improved safety-wheel on the rear 10 end of a roller skate to enable the skater to regain his equilibrium very easily and rapidly.

The invention consists in the combination, with a roller-skate, of prongs projecting downward from the rear end, and having a series 15 of apertures for receiving a pin, a pin in one pair of apertures, and a roller mounted between the prongs on the pin and having a series of eccentric apertures for receiving a locking-pin for locking the roller in place.

Reference is to be had to the accompanying 20 drawings, forming part of this specification, in which similar letters of reference indicate corresponding parts in both the figures.

Figure 1 is a side view of a roller-skate provided with my improved safety wheel. Fig. 25 2 is a rear view of the same.

On the rear or heel end of the foot-plate A of the roller-skate a plate, B, is secured, from which two prongs, C, extend downward, and 30 are then inclined downward and toward the rear, the lower parts, C', of the prongs having a series of apertures, D, for receiving the ends of a pin, E, passed through the middle of the roller F between the said prongs. The pin E 35 can be passed through the lower, middle, or upper apertures D, accordingly as the roller is to be held a greater or less distance above the floor. The roller F also has eccentric apertures H, through which a pin, J, can be passed, 40 the said pin being also passed through apertures D in the prongs, whereby the roller F is locked in place. When the roller is not to be locked, the pin J is held in apertures in the prongs C, near their upper ends. Adepts and 45 experts need not have the roller F locked, as they are more experienced and can regain their equilibrium very easily. In case the skater is about to fall toward the rear, the roller F

comes in contact with the floor and enables the skater to regain his equilibrium. As the 50 roller is free to turn, it does not act as a brake, and does not check the speed of the skater, which is of great importance, for if a person suddenly stopped in a crowded rink a number of other persons would also be stopped 55 and considerable disorder would arise, and accidents might happen, as others would not check their speed at the same time. The roller F does not interfere with fancy or backward skating, as it is held sufficiently above 60 the floor. Beginners lock the roller F in place by means of the pin J, so that the roller acts as a brake and checks the speed of the skater as soon as it is brought in contact with the floor. As the roller F has a series of apertures, H, it can be locked in different positions by the pin J, so that the same part of the rim 65 will not always come in contact with the floor.

Having thus described my invention, what I claim as new, and desire to secure by Letters 70 Patent, is—

1. The combination, with a roller-skate, of prongs projecting down from the rear end and having a series of apertures for receiving a pin, and of a roller mounted between 75 the prongs on said pin, substantially as herein shown and described.

2. The combination, with a roller-skate, of prongs projecting down from the rear end and having a series of apertures, of a pin 80 held in one pair of apertures, and of a roller mounted between the prongs on the said pin and having a series of eccentric apertures, substantially as herein shown and described.

3. The combination, with a roller-skate, of 85 the prongs C, projecting downward from the rear end, the pin E in said prongs, the roller F on the pin, which roller has a series of eccentric apertures, and of the pin J, held in the prongs, substantially as herein shown and described. 90

ROSSETER I. TOWLE.
